UNITED STATES PATENT OFFICE

165,715

HAT

Velma D. Johnson, Portland, Oreg.

Application February 10, 1947, Serial No. 136,819

Term of patent 14 years

(Cl. D3—13)

To all whom it may concern:

Be it hereby known that I, Velma D. Johnson, a citizen of the United States, residing at Portland, in the county of Multnomah and State of Oregon, have invented a new, original, and ornamental Design for Hats, of which the following is a specification, reference being had to the accompanying drawing, forming a part thereof.

Fig. 1 is a side elevational view of a hat showing my new design.

Fig. 2 is a side perspective view and

Fig. 3 is a top plan view thereof as it appears in flattened position; the hat being similarly ornamented on the bottom.

I claim:

The ornamental design for a hat, as shown and described.

VELMA D. JOHNSON.
